HAT RACK

James J. Mangin, Youngstown, Ohio

Application March 9, 1954, Serial No. 29,441

Term of patent 14 years

(Cl. D80—10)

To all whom it may concern:

Be it known that I, James J. Mangin, a citizen of the United States, residing at Youngstown, in the county of Mahoning and State of Ohio, have invented a new, original, and ornamental Design for a Hat Rack, of which the following is a specification, reference being had to the accompanying drawing forming a part thereof.

The figure is a perspective view of a hat rack, showing my new design.

I claim:

The ornamental design for a hat rack, as shown.
